UNITED STATES PATENT OFFICE.

FRANK HIGHTOWER, OF MONTROSE, COLORADO.

EXCAVATOR.

1,245,590.

Specification of Letters Patent.

Patented Nov. 6, 1917.

Application filed May 31, 1916. Serial No. 100,912.

To all whom it may concern:

Be it known that I, FRANK HIGHTOWER, a citizen of the United States, residing at Montrose, in the county of Montrose and State of Colorado, have invented certain new and useful Improvements in Excavators, of which the following is a specification, reference being had to the accompanying drawings.

10 This invention relates to certain improvements in excavators and has relation more particularly to a device of this general character especially designed and adapted for use in the digging of trenches or ditches; 15 and it is an object of the invention to provide a device of this general character including a plow and carrier together with novel and improved means whereby a side delivery may be given to the matter 20 excavated.

It is also an object of the invention to provide an excavator with a novel and improved discharging conveyer which is disposed laterally of the machine proper and 25 which is capable of endwise adjustment so that the matter excavated may be discharged at the same side of the trench or ditch upon travel of the excavator in opposite directions.

30 The invention consists in the details of construction and in the combination and arrangement of the several parts of my improved excavator whereby certain important advantages are attained and the device is rendered 35 simpler, less expensive and otherwise more convenient and advantageous for use, all as will be hereinafter more fully set forth.

The novel features of the invention will hereinafter be definitely claimed.

40 In order that my invention may be the better understood, I will now proceed to describe the same with reference to the accompanying drawings, wherein—

Figure 1 is a view in side elevation illustrating an excavator constructed in accordance with an embodiment of my invention;

Fig. 2 is a view in top plan of the device as disclosed in Fig. 1;

Fig. 3 is a sectional view taken substantially on the line 3—3 of Fig. 2; and

Fig. 4 is a fragmentary view partly in elevation and partly in section taken adjacent the upper end of the elevating conveyer as herein set forth.

55 As disclosed in the accompanying drawings, A denotes the axle on which is loosely

mounted the supporting and driving wheels W. On the axle A at a point adjacent one of the wheels W is mounted the spur gear G provided with the ratchet teeth R for the 60 engagement of spring backed pawl P carried by the wheel W so as to permit freedom of motion to the wheel W incident to the backing or turning of the machine.

B denotes the body of the machine and 65 is rested intermediate its length upon the axle A and adapted for rocking movement therearound, and the forward end of the frame is provided with the shovel or plow S for working the ground or other ma- 70 terial to be excavated.

F is a truck having for its purpose to support the forward portion of the body and said truck F is provided with the pole D and at its ends with the caster wheels E 75 to facilitate turning of the machine at the ends of a ditch or trench. The truck F is connected with the side bars B of the body through the medium of the draw bars H and the beams J. 80

The beams J are fixed to and extend upwardly and forwardly from the side bars B and are provided with the segmental rack K and a lever L provided with a detent M for engaging the rack K while the draw 85 bars H are pivoted, as at a, to the beams J and are connected through the medium of the link b with the lower and forward end of the lever L. Thus it will be apparent that the forward portion of the machine 90 body may be raised and lowered and adjustably fixed at various heights as conditions may require.

1 and 2 denote rollers interposed between and rotatably supported by the opposite end 95 portions of the side bars B and around which travels the endless apron 3 for receiving the earth or the like from the shovel or plow S and carrying the same upwardly and rearwardly. The upper roller 2 is operatively engaged, as at 4, with the spur gears G whereby the requisite travel is imparted to the apron 3 upon advance of the machine. 100

Suitably supported by the side bars B is a frame T including the vertically disposed 105 members 5 arranged in pairs in longitudinal alinement with each of the side bars B and each pair of members 5 is provided with the vertically spaced guide rollers 6 between which are mounted for sliding movement the 110 side bars 7 of the discharge conveyer, where- by it will be perceived that said conveyer is

capable of endwise movement. The adjacent ends of the side bars 7 have interposed therebetween and rotatably supported thereby the rollers 8 around which is disposed the 5 apron 9 and each of said rollers 8 has a forwardly extending shaft 10 to which is affixed a gear 11 for a purpose which will hereinafter be more fully explained.

The endless apron 3 discharges upon the 10 apron 9 and it will be at once apparent that by imparting the requisite endwise movement to the discharge conveyer, the apron 9 may be caused to discharge at the same side of a ditch or trench as the machine is caused 15 to travel forwardly and backwardly during the excavating operation.

The upper end portions of the members 5 are tied or connected by the transversely directed beams 12 which rotatably support the 20 shaft 14 disposed longitudinally of the machine and provided with the sprockets 15 positioned substantially directly above the side bars 7 and over which are disposed the sprocket chains 16 which have their end portions secured to the opposite extremities of 25 the side bars 7. The shaft 14 is provided with an operating member 17 whereby the requisite axial rotation may be imparted thereto in order to move the discharge conveyer in the direction desired in accordance 30 with the requirements of practice.

Rotatably supported by the side bars B is the shaft 18 arranged substantially in parallelism with the discharge conveyer and operatively engaged, as at 19, with a movable part of the machine for imparting the requisite rotation thereto. The extremities of the shaft 18 are provided with the gears 20 which coact with the gears 11 to limit the 40 endwise movement of the discharge conveyer and to coact therewith to impart the requisite travel to the apron 9.

From the foregoing description, it is thought to be obvious that an excavator constructed in accordance with my invention is 45 of an extremely simple and comparatively inexpensive nature and is particularly well adapted for use by reason of the convenience and facility with which it may be assembled, and it will also be obvious that my invention 50 is susceptible of some change and modification without material departure from the principles and spirit thereof and for this reason I do not wish to be understood as limiting myself to the precise arrangement and 55 formation of the several parts herein shown in carrying out my invention in practice.

I claim:

An excavator including a portable body, a frame arranged at an end of the body and including vertically disposed members arranged in pairs, said pairs of vertically disposed members being transversely spaced relative to the body, the vertically disposed members of each pair having their opposed faces provided with vertically spaced rollers, a frame comprising spaced side boards mounted for sliding movement between said rollers, a horizontal shaft supported by the first named frame at substantially the transverse center of the body and provided with operating means, and a flexible member co-acting with each of the side boards of the second frame and having its extremities secured to the opposite end portions of the side board, the intermediate portion of said flexible member being operatively engaged with the shaft.

In testimony whereof I hereunto affix my signature in the presence of two witnesses.

FRANK HIGHTOWER.

Witnesses:

JOHN C. BELL,
B. E. HANES.
